(57) **CLAIM**

The ornamental design for a measuring scoop, as shown and described.

DESCRIPTION

FIG. 1 is a front perspective view of a first embodiment of my design;

FIG. 2 is a front view thereof;

FIG. 3 is rear view thereof;

FIG. 4 is right side view thereof;

FIG. 5 is left side view thereof;

FIG. 6 is top view thereof;

FIG. 7 is bottom view thereof;

FIG. 8 is a front perspective view of a second embodiment of my design;

FIG. 9 is a front view thereof;

FIG. 10 is rear view thereof;

FIG. 11 is right side view thereof;

FIG. 12 is left side view thereof;

FIG. 13 is top view thereof;

FIG. 14 is bottom view thereof;

FIG. 15 is a front perspective view of a third embodiment of my design;

FIG. 16 is a front view thereof;

FIG. 17 is rear view thereof;

FIG. 18 is right side view thereof;

FIG. 19 is left side view thereof;

FIG. 20 is top view thereof;

FIG. 21 is bottom view thereof;

FIG. 22 is a front perspective view of a fourth embodiment of my design;

FIG. 23 is a front view thereof;

FIG. 24 is rear view thereof;

FIG. 25 is right side view thereof;

FIG. 26 is left side view thereof;

FIG. 27 is top view thereof;

FIG. 28 is bottom view thereof;

FIG. 29 is a front perspective view of a fifth embodiment of my design;

(Continued)

FIG. 30 is a front view thereof;
 FIG. 31 is rear view thereof;
 FIG. 32 is right side view thereof;
 FIG. 33 is left side view thereof;
 FIG. 34 is top view thereof;
 FIG. 35 is bottom view thereof;
 FIG. 36 is a front perspective view of a sixth embodiment of my design;
 FIG. 37 is a front view thereof;
 FIG. 38 is rear view thereof;
 FIG. 39 is right side view thereof;
 FIG. 40 is left side view thereof;
 FIG. 41 is top view thereof;
 FIG. 42 is bottom view thereof;
 FIG. 43 is a front perspective view of a seventh embodiment of my design;
 FIG. 44 is a front view thereof;
 FIG. 45 is rear view thereof;
 FIG. 46 is right side view thereof;
 FIG. 47 is left side view thereof;
 FIG. 48 is top view thereof;
 FIG. 49 is bottom view thereof;
 FIG. 50 is a front perspective view of an eighth embodiment of my design;
 FIG. 51 is a front view thereof;
 FIG. 52 is rear view thereof;
 FIG. 53 is right side view thereof;
 FIG. 54 is left side view thereof;
 FIG. 55 is top view thereof;
 FIG. 56 is bottom view thereof;
 FIG. 57 is a front perspective view of a ninth embodiment of my design;
 FIG. 58 is a front view thereof;
 FIG. 59 is rear view thereof;
 FIG. 60 is right side view thereof;
 FIG. 61 is left side view thereof;
 FIG. 62 is top view thereof;
 FIG. 63 is bottom view thereof;
 FIG. 64 is a front perspective view of a tenth embodiment of my design;
 FIG. 65 is a front view thereof;
 FIG. 66 is rear view thereof;
 FIG. 67 is right side view thereof;
 FIG. 68 is left side view thereof;
 FIG. 69 is top view thereof; and,
 FIG. 70 is bottom view thereof.

The broken lines shown in the drawings represent portions of the measuring scoop which form no part of the claimed design.
